(No Model.)

S. H. JENKINS.

AUTOMATIC RAILWAY SWITCH.

No. 324,773.

Patented Aug. 18, 1885.

Inventor:
Samuel H. Jenkins

UNITED STATES PATENT OFFICE.

SAMUEL H. JENKINS, OF NEW YORK, N. Y.

AUTOMATIC RAILWAY-SWITCH.

SPECIFICATION forming part of Letters Patent No. 324,773, dated August 18, 1883.

Application filed January 27, 1883. (No model.)

To all whom it may concern:

Be it known that I, SAMUEL H. JENKINS, of the city, county, and State of New York, have invented certain new and useful Improvements in Combined Railway Switches and Frogs, of which the following is a full, clear, and exact description, reference being had to the accompanying drawings, and to the letters of reference marked thereon.

10 My invention relates especially to mechanism employed upon railways for transferring locomotives, cars, or trains from one set of rails to another; and it has for its object the provision of a combined switch and frog 15 wherein the fixed rails cannot move from their proper position and wherein absolute safety is obtained, rendering it impossible that a locomotive, car, or train passing over the switch and the parts of the track combined therewith shall become derailed, causing 20 loss of life or destruction of property.

To attain the desired end my invention consists, essentially, in a V-shaped rail, taking the place of the ordinary frog, said rail being 25 secured to the extremities of the stationary rails by means of fish-plates, and resting upon a bed-plate, to which the stationary rails are riveted or bolted, in such a manner that its point may move to the right or left, such 30 movement being limited by stops secured to or forming a part of the bed-plate. The point of the V-shaped rail extends between the wing-rails of the main and side track, each of said rails being immovably secured to said 35 bed-plate, which in turn is securely spiked to the ties. Affixed to the V-shaped rail, near its point, is an operating-rod extending to the crank of a shaft whereon is located a throwing-bar. A suitable spring is interposed in 40 the operating-rod, in order to permit the automatic movement of the V-shaped rail by the flanges of the wheels of trucks passing along either track when the frog is not placed in proper position for such track. The switch 45 with which the V-shaped rail is connected is located upon the main track, the rails forming said switch terminating in needle-points, the other extremities of the switch-rails being secured by fish-plates to the stationary rails, 50 and connected together by bars in the usual manner. The foot of the switch-rails next to

the main-track rails is cut away in such a manner as to permit them to lie closely thereagainst and pass above the foot of the main-line rails, being held in this raised position 55 by means of ways or supports secured to or forming a part of the longitudinal bed-plate, to which the fixed rails of the track are secured. The above-mentioned ways or supports serve also to hold the fixed rails securely 60 to the bed-plate upon the inside, the outside being double-spiked to said plate and to the ties. An operating-rod secured to the switch extends to a crank upon the shaft, to which the throwing rod or bar is attached, said 65 shaft operating both the V-shaped rail or frog and the switch. A spring is interposed in the rod connected to the switch, in order to permit the automatic movement of the rails by the flanges of passing wheels in case the 70 switch should not be in proper position when a train passes over it, all of which will be hereinafter first fully described, and then pointed out in the claims.

In the drawings, Figure 1 is a plan view of 75 my improved combined switch and frog. Fig. 2 is a cross-sectional view at the operating-bar of the switch in Fig. 1. Fig. 3 is a view in elevation of one of the guides for the operating-rod of the switch, the ties to which it 80 is secured being shown in section. Fig. 4 is a longitudinal sectional view of one of the bed-plates of the switch. Fig. 5 is a longitudinal sectional view of the spring interposed in the operating-rod of the V-shaped 85 rail. Fig. 6 is a vertical longitudinal sectional view of a fragment of the bed-plate beneath the V-shaped and wing rails.

Like letters of reference wherever they occur indicate corresponding parts in all the figures. 90

A³ are the ties upon which the rails and bed-plates are laid. D is a metal bed-plate secured to the ties. A are the rails of the main track, and B are the rails of the side track.

P is a V-shaped rail which takes the place 95 of the ordinary frog. Said V-shaped rail is secured to the fixed rail of the main and side tracks by means of fish-plates W, the foot of said rail resting upon the bed-plate D, and extending between the wing-rails N, the said 100 wing-rails being securely bolted or riveted to the bed-plate. The foot of these wing-rails is

cut away upon the inside to permit the rail P to lie snugly thereagainst when turned to either side.

O are stops or ears secured to or formed upon plate D, said stops limiting the lateral movement of rail P. The rails of both the main and side tracks are riveted to bed-plate D at Q, and any movement of the track in a longitudinal direction must always be uniform, 10 and thus it is impossible that the parts of the device should become displaced.

X is an operating-rod secured to a bar, X³, which is riveted or bolted to rail P. A depression, B³, is formed in plate D for the passage of bar X³, as illustrated in Fig. 6. A spring, R, is located between the two parts of rod X, one of said parts having a right-hand and the other a left-hand screw-thread cut thereon, engaging with nuts S, for the purpose of taking up or letting out the tension of the spring, as may be required. The nuts S are cast upon the spring R, and are provided with an eight-sided shoulder, T, to which a wrench may be applied for regulating the tension. 25

V are guides secured to ties, rod X passing through said guides, which serve to keep it in a proper position and prevent buckling of the spring. The extremity of rod X engages 30 with a crank, C³, upon a shaft, A', to which a throwing-bar, D³, is affixed in the usual manner.

D' are longitudinal bed-plates, to which the main-track rails and the extremities of the 35 side-track rails are firmly secured.

Care needle-pointed rails forming the switch, said rails being connected by bars F, and secured to rails A and B by means of fish-plates W. The foot of each rail upon the side next 40 the fixed rail is cut away in order to permit the switch-rails to press or lie closely against said fixed rails in the well-known manner.

E are supports or ways secured to or forming a part of the bed-plates D', supporting the 45 rails of the switch, and extending over the foot of the fixed rail at y in such a manner as to firmly hold it in place upon the inside, the outside being secured by double spikes Z, passing through the bed-plate and into the ties. 50 I have shown the ways E as being riveted to bed-plates D'; but as said plates are constructed of wrought-iron, slots may be cut at the necessary points, and by turning the metal upward at the edges of the slots the ways or 55 supports may be readily formed upon the plate itself.

H is an operating-rod attached to a connecting-bar at G. This rod is bifurcated, the forks thereof being screw-threaded their entire 60 length. Locking-nuts K engage with these screw-threads, holding the guides L in place, and by which the tension of the spring R may be regulated, said spring being supported upon a rod, H', passing through the guides L, which 65 play upon horizontal plates M, secured to the edges of ties A³, as illustrated in Fig. 3. Rod

H' passes through guides L, and engages with a crank, C³, upon the shaft A'. This arrangement permits the movement of the rails of the switch by the flanges of passing wheels, as before described for rail P. 70

When all the parts of the device are in the position shown in Fig. 1, a continuous, unbroken track is formed for the main line both over the frog and switch. If a locomotive, 75 car, or cars should now pass from the side to the main track, the flanges of the wheels would throw the point of the rail P to the left, and then the rails of the switch in turn, safely passing thereover, leaving the main track 80 still in proper shape for the passage of trains thereover, the switch and rail P being returned to their former position by the action of springs R.

In order to place the switch and frog in 85 proper position for the passage of cars to the side track, the throw-bar D³ is reversed in position, bringing the switch-rails and rail P to the left, forming a continuous, unbroken line of rails from the main to the side track. 90 Should a train now come from the right upon the main track, the flanges of the wheels would press rail P and the switch-rails to the right, safely passing both frog and switch, when the parts of the device would be automatically restored to their former position. 95

Having now fully described my invention, what I claim as new therein, and desire to secure by Letters Patent, is—

1. In automatic safety railway-switches, the 100 combination of longitudinal plates whereon are formed or secured bearings for movable needle-point rails, movable needle-point rails supported on said bearings substantially upon a level with fixed main-line and side-track 105 rails secured to said plates firmly at each end thereof beyond the heels and points of said movable needle-point rails, the fixed main-line and side-track rails outside of said movable needle-point rails being spiked to the 110 ties through the plate on the outside, and held in place by said bearings projecting over the foot of these fixed rails on the inside, substantially as shown and described.

2. The herein-described combined safety 115 switch and frog, consisting of the needle-pointed switch-rails mounted upon supports secured to or formed upon the longitudinal plates D', to which the rails A and B are secured, as set forth, the frog consisting of the 120 V-shaped rail P, mounted upon the plate D, the said needle-pointed switch and the frog being provided with an operating-rod wherein is located the spring, as shown, said rods connecting with cranks upon the operating-shaft, the whole arranged to be operated automatically by the flanges of passing wheels or by means of the said shaft, as set forth. 125

3. In a device of the character herein specified, the bifurcated rod H, the forks thereof being screw-threaded for their entire length, as set forth, guides L, plates M, spring R, rod

H', and the regulating or locking nuts K, the whole combined and arranged to operate substantially as shown and described.

4. In automatic safety railway-switches, the combination of longitudinal plates having bearings for movable needle-point rails supported thereon, fixed main-line and side-track rails secured to said plates beyond the heels of said movable rails, said fixed rails outside of said movable rails being secured to the ties on the outside, and held from turning by said bearings projecting over their feet on the inside, substantially as shown and described.

5. In automatic safety railway-switches, the combination of movable needle-point rails supported on bearings on longitudinal plates, to which fixed main and side track rails are secured beyond the heels of said movable rails, a movable V-shaped rail supported on a lon-

gitudinal plate secured to the fixed inside 20 main and side track rails beyond the heel of the V-shaped rail and to the wings of the fixed inside main and side track rails near the other end of said plate, and connecting and operating rods and springs, all arranged substantially as set forth, for automatic operation by flanges of passing car-wheels, substantially as shown and described.

In testimony that I claim the above as my true and lawful invention I hereunto subscribe my signature and affix my seal, in the presence of two witnesses, in the city, county, and State of New York, this the 23d day of January, 1883.

SAMUEL H. JENKINS. [L. S.]
